UNITED STATES PATENT OFFICE.

HERMAN HERMANSEN, OF BAYBRIDGE, OHIO, ASSIGNOR TO THE SANDUSKY CEMENT COMPANY, OF CLEVELAND, OHIO.

GAS WASHING AND COLLECTING APPARATUS.

1,283,763.

Specification of Letters Patent.

Patented Nov. 5, 1918.

Application filed December 28, 1916. Serial No. 139,394.

To all whom it may concern:

Be it known that I, HERMAN HERMANSEN, a citizen of the United States, residing at Baybridge, in the county of Erie and State of Ohio, have invented certain new and useful Improvements in Gas Washing and Collecting Apparatuses; and I do declare the following to be a full, clear, and exact description of the invention, such as will enable others skilled in the art to which it appertains to make and use the same.

This invention relates to improvements in machines for collecting and washing gases and the like.

The principal object of the invention is to provide an apparatus by which useful gases from furnaces and the like which are ordinarily wasted, may be collected and conserved for future use.

An additional object is to provide such an apparatus with an improved means for spraying liquid into a chamber in which the gas is liberated.

With these and many other objects in view, the invention resides in the novel features of construction, combination and arrangement of parts which will be hereinafter more particularly described and claimed and shown in the drawings wherein:

Figure 1 is a top plan view of the apparatus;

Fig. 2 is a vertical section on substantially the line 2—2 of Fig. 1; and

Fig. 3 is a detail vertical section on the line 3—3 of Fig. 2.

The apparatus shown in the accompanying drawings has gas fed thereto from the furnace, kiln, or other machine (not shown) by way of the flue or inlet pipe 1, said pipe extending into a substantially cylindrical chamber 2. This gas inlet pipe 1 extends through the flat inclined bottom 3 of the chamber and into the interior thereof where it opens adjacent the top 4, said top being also flat and preferably in a horizontal plane. A horizontal partition 5 is spaced from the top 4 and secured to the side of the chamber so as to form a compartment 6 in the upper part of the latter, said partition having a central opening to receive the end of the inlet pipe 1 which is fixed thereto in any preferred manner.

The natural upward flow of the gas in the inlet pipe 1 is increased by means of a jet

which enters through the side of the pipe below the bottom 3 of the chamber. The steam or the like from this jet not only increases the draft within the pipe 1 but also tends to condense the gas passing therethrough. The direction of the flow of gas and steam is reversed when it enters the compartment 6, it passing out of said compartment through the downwardly extending outlet pipes 8 and into the main portion of the chamber 2. These outlet pipes 8 are disposed in an annular series as shown in Fig. 1, the partition 5 being provided with openings to receive the upper ends of the pipes, their lower ends terminating adjacent the bottom 3. The direction of flow of gas and steam is shown by the arrows in Fig. 2.

The gas is further condensed and collected by water or other liquid which sprays from the ends of spray tubes 9, one end of which extends through the top 4 of the compartment 6 into each of the outlet pipes 8. The gases not affected by the water or other liquid used pass through the outlet pipes 8 and out through the pipe 19 into the chamber 20. Here they pass underneath the hood 25 and out through the outlet pipe 26. In each of the outlet pipes there is located spray members 9 in the form of an upright tube having a valve seat 10 formed in its lower end while its upper end is coupled to a connecting pipe 11, and a valve stem 12 extending throughout the length of the tube and having a cone-shaped valve 13 formed on its lower end, its upper end being screw threaded as at 14. The valve 13 being cone-shaped, it is obvious that the liquid from the tube will be sprayed downwardly toward the sides of the pipe 8 in which said tube is disposed, the intensity of the spray being regulated by the position of the valve with respect to its seat.

This regulation is accomplished by means of a pair of adjusting nuts 15 disposed one on each side of the horizontal portion 16 of an inverted U-shaped bracket 17, the free ends of the arms of said bracket being secured to the top 4 directly over the tube 8 in which the spray member is disposed. By adjusting the nuts 15 in the proper directions the valve 13 is moved toward or away from its seat 10. One of the brackets 17 is positioned over each of the outlet pipes 8 and secured to the top 4, thereby aiding in supporting the spray members 9. The main

support for the same, however, is provided by the brackets 18 secured to the top 4 and in which the connecting pipes 11 are held.

The liquid from the spray tubes after being saturated by the gases from the inlet pipe 1 drops through the pipes 8 to the inclined bottom of the chamber 2 where it flows out through the pipe 19 at the lowest point in said chamber. The pipe 19 is connected to the top of a tank 20 which is positioned in a plane below the chamber 2. In the upper portion of this tank 20 is a filter 21, through which the saturated liquid flows before reaching the bottom where it is collected and retained until it is ready to be pumped out or drawn off through a drain cock 22.

The liquid contained in the tank 20 is passed through the chamber 2 several times, or until it becomes sufficiently saturated with the gases which are forced into said chamber, it being pumped from the tank by way of the pipe line 23 and the pump P. After passing through the pump it is forced out through the pipe 24 which connects with the pipes 11. From these pipes it is distributed through the several spray tubes to the interior of the chamber 2.

In the operation of the invention, it is obvious that the several figures of the drawings show what is briefly described as follows:—As hereinbefore mentioned, the gases pass from the furnace or the like through the pipe 1 in to the compartment 6 and then through the outlet pipes 8 into the main portion of the chamber 2, the liquid being sprayed into said pipes 8 to provide a medium whereby the gas may be collected. This medium is lead into the tank 20 where it is filtered to remove extraneous matter before it is pumped by the pump P back through the pipes which feed the spray tubes 9. Thus, a continuous cycle of operation is being made by the same liquid, this movement of the liquid being continued until it becomes too thick to spray through the tubes 9, or until it is sufficiently saturated, whereupon it is drawn from the tank 20 by the drain cock 22. Although the above described apparatus is primarily used for washing and collecting gases, it is obvious that various other uses may be made of the same with slight modifications.

Having thus described my invention, what

55 I claim is:—

1. An apparatus of the class described comprising a chamber, a horizontal partition across the upper end of said chamber to form a horizontal compartment, an inlet pipe centrally disposed in said chamber and extending upwardly through said partition, a plurality of outlet pipes arranged in an annular series and depending from said partition and extending to a point adjacent the bottom of said chamber, a fluid spray tube

extending through the top of the chamber and compartment into each of said outlet pipes, and an outlet pipe from the bottom of said chamber.

2. An apparatus of the class described comprising a chamber, a horizontal partition across the upper end of said chamber to form a horizontal compartment, an inlet pipe centrally disposed in said chamber and extending upwardly through said partition, a plurality of outlet pipes arranged in an annular series and depending from said partition and extending to a point adjacent the bottom of said chamber, a fluid spray tube extending through the top of the chamber and compartment into each of said outlet pipes, an outlet pipe from the bottom of said chamber, and means for regulating the flow of the fluid through each of the spray tubes located outside of the compartment.

3. An apparatus of the class described comprising a chamber, a compartment at the upper end of the chamber, a gas inlet into said compartment, a plurality of outlet pipes depending from the bottom of the compartment, a spray member disposed in each of said pipes, each comprising a tube extending through the top of the chamber and having a valve seat in its lower inner end, an inverted U-shaped bracket secured to the top of the chamber, a stem extending through said tube and having a valve for engaging said seat, means in conjunction with said bracket and stem for adjusting said valve, and an outlet from the bottom of said chamber.

4. An apparatus of the class described comprising a chamber, a compartment at the upper end of said chamber, a gas inlet into said compartment, a plurality of outlet pipes depending from the bottom of the compartment and opening into said chamber, a spray member disposed in each of said pipes, each comprising a tube extending through the top of the chamber and having a valve seat in its lower inner end, an inverted U-shaped bracket secured to the top of the chamber, said bracket having an opening in its horizontal portion, a stem extending through said tube, the upper end being threaded and extended through the opening in said bracket, a valve on the lower end of said stem for engagement with said seat, a pair of adjusting nuts on the threaded end of said stem, one being disposed on each side of the horizontal portion of said bracket, whereby to adjust said valve with respect to its seat, a pipe mounted on the top of said chamber and connecting all of said spray tubes, and an outlet pipe from the bottom of said chamber.

5. A gas collecting apparatus comprising in combination, a chamber having a compartment in its upper end, a gas inlet into said compartment, a plurality of outlet pipes de-

pending from the bottom of said compartment, a spray member disposed in each of said pipes and extending through the top of said chamber, a pipe connecting the upper ends of each of said spray members, an outlet pipe extending from the bottom of said chamber, a storage tank having the last mentioned outlet pipe opening through its top, a pump, a pipe connecting said pump with the bottom of said tank, and a second pipe connecting the pump with the pipe

joining the spray members, whereby liquid is pumped from the tank and distributed through the spray members into said chamber.
